UNITED STATES PATENT OFFICE.

MORRIS S. TOWSON AND CLYDE E. COCHRAN, OF CLEVELAND, OHIO, ASSIGNEES TO THE ELWELL-PARKER ELECTRIC COMPANY, OF CLEVELAND, OHIO, A CORPORATION OF OHIO.

INDUSTRIAL TRUCK.

1,364,416.

Specification of Letters Patent.

Patented Jan. 4, 1921.

Application filed March 10, 1919. Serial No. 281,774.

To all whom it may concern:

Be it known that we, MORRIS S. TOWSON and CLYDE E. COCHRAN, citizens of the United States, residing at Cleveland, in the 5 county of Cuyahoga and State of Ohio, have invented a certain new and useful Improvement in Industrial Trucks, of which the following is a full, clear, and exact description, reference being had to the accompanying 10 drawings.

This invention relates to an industrial automobile truck having a load support adapted to be tilted by power mechanism, enabling the truck to receive a suitable 15 standing load, tip it over above the running gear of the truck and then, after transporting it, deposit it in the standing position.

The invention is shown as embodied in a truck designed particularly for handling 20 large rolls of paper, such as are used for web printing presses. In such embodiment there is provided the truck proper with its running gear and propelling mechanism, and a suitable platform hinged adjacent to 25 the rear end of the truck, and mechanism for tipping the platform about such pivot into an approximately upright position in which the upright roll of paper may be secured to it, the reverse movement of such 30 tipping mechanism then restoring the platform to a substantially horizontal position for transportation. This particular form of our load handling truck is shown in the drawings hereof and is hereinafter more 35 fully described. The essential characteristics of the invention, which are illustrated by this embodiment, are set out in the claims.

In the drawings, Figure 1 is a side elevation of the truck, showing in full lines the 40 platform in transportation position with a roll of paper thereon and showing in broken lines the position of the platform as it is discharging such load or just as it has received the load before tipping it into horizontal position; Fig. 2 is a side elevation of the truck with the platform in the load-receiving or discharging position; Fig. 3 is a plan, partly broken away, of the linkage system and operating mechanism for tilting 45 the platform; Fig. 4 is a cross section through the platform and the paper roll carried thereby; Fig. 5 is a transverse sectional elevation of the motor and the worm gearing driven thereby; Fig. 6 is a longitudinal sec-

tional elevation of the operating screw and 55 the worm wheel which constitutes a nut therefor, this view being at right angles to Fig. 5.

As shown in Figs. 1 and 2, 10 indicates the frame or body of the truck, which is supported by rear wheels 11 and a pair of forward wheels 12. These forward wheels are on opposite sides of a front housing 13 composed of upright and transverse members secured to the frame bars 10. This housing 60 carries a suitable motor 14 for driving the front wheels and has a space 15 above for a storage battery. The front wheels are steered in any suitable manner, as indicated by the steering lever 16. The construction 65 of the frame, wheels, motor, etc., already described does not enter into the present invention. They may be formed, if desired, according to Patent No. 1,260,145, granted 70 March 19, 1918, to The Elwell-Parker Electric Company as assignee of Clyde E. Cochran. 75

In the present invention we secure to the frame bars 10 at their rear ends, a pair of brackets 20 which extend upwardly and 80 rearwardly. At their upper ends these brackets pivotally carry the cradle or platform which receives the load, and will be specifically varied in form according to the character of the load. As shown, this platform 85 consists of a pair of outwardly facing channel beams 30 and an intermediately depressed cross plate 31 secured to the upper flanges of the channel beams. The depression is adapted to laterally position a roll of 90 paper designated A. The pivoting of the brackets 20 to these beams is shown as effected by a transverse shaft 25 connecting the upper ends of the brackets 20 with eyes in blocks 32 secured to the under sides of 95 the beams 30. The construction described makes an effective and firm pivoting of the platform to the truck frame.

To operate the platform, we connect it by a linkage and gear system with a motor 100 mounted in the housing 13, the motor and gearing being arranged to pull or push a rod longitudinally, which operates the linkage system. This will now be described.

Each of the brackets 20 has a portion extending downwardly at the rear end of the truck frame. To these downward extensions are pivoted at 26 a pair of links 40, the 105

upper ends of which are connected by a cross shaft 41. This shaft is connected by links 42 with the platform. These links 42 are shown as having eyes on their forward ends surrounding the shaft 41, and at their rear ends having eyes through which extend pins into blocks 44 secured to the inner faces of the platform frame bars.

The central portion of the shaft 41 is em-
10 braced by an eye in the end of a main link 45 which at its forward end has an eye embracing a shaft 46. This shaft is mounted in the upper ends of a pair of arms 47 pivoted at their lower ends to brackets 48 carried by the truck frame bars 10. This piv-
15 oting is shown as effected by means of a through-shaft 49 extending across the truck frame.

In the arms 47 we mount a transverse rod
20 50 which is embraced by an eye 51 on the rear end of the push and pull rod 52. This push and pull rod may be said to form the operating member of the linkage system de-
25 scribed. It is suitably connected with the motor driven gearing and furnishes the means for actuating the main link 45. This will be hereinafter described. For the present it may be noted that a forward pull on
30 this main link carries the mechanism into the ultimate position shown in Fig. 2, where-
35 in the platform is nearly vertical, whereas a rearward push on this link shoves on the toggle knuckle 41, straightening the toggle composed of the links 40 and 42 and bring-
40 ing the platform into the horizontal position shown in Fig. 1.

It will be seen from Fig. 1 that when in
45 transporting position the bulk of the load is carried by the shaft 25 and brackets 20 to the truck frame. A portion of the load is carried by a horizontal bracket 18 secured to the rear face of the forward housing 13. The straightened toggle makes a strut be-
50 tween the rear portion of the load and the lower end of the brackets 20 and steadies the load.

Rolls of paper are frequently stored on
55 their ends. When used for transporting such roll, the roll may first be very readily tipped up slightly on one edge and the truck with its platform or cradle upright backed against the roll so that a cleat 35 on the rear or lower end of the cradle lies beneath the elevated bottom edge of the roll; then the
60 roll is tipped over in the other direction to lie against the cradle and is secured by passing a cable around the upper portion thereof, as illustrated in Fig. 2, where the cable 38 extends about the roll and at its ends hooks on to pins 39 extending outwardly from the cradle beams.

After the roll of paper has been clamped to the cradle, a push on the rod 52 shoves the linkage system rearwardly, shoving on
65 the toggle joint 41, straightening the toggle

to tip the load over in the position shown in full lines in Fig. 1. After the center of gravity of the load has passed to the front of the shaft 25 the weight of the load tends to assist in the straightening of the toggle, 70 and the mechanism of the operating rod 52 then holds back the load to prevent too rapid descent. In unloading, a pull on the rod 52 swings the load into the position shown in Fig. 2, whereupon the cable clamp 38 is 75 removed and the roll tipped into a more nearly vertical position, after which the truck pulls away from it, allowing the cleat 35 to clear the roll, leaving it standing up-
80 right in its new position.

It will be seen from the description of operation that the mechanism must be able to effect at will a pull or push on the rod 52 and to hold that rod against movement independently of such mechanism. The operating mechanism which we have shown for effecting this push and pull is substantially that shown, described and claimed in the patent heretofore mentioned. It will be now more fully explained.

The push-and-pull rod 52 extends into a housing 60 which is provided with trunnions 61 pivoting it to frame brackets 62 carried by the truck frame. Within this housing the rod carries an external screw 90 thread 63 (Fig. 6). Surrounding this thread and journaled in the housing is a nut 64 which carries worm teeth 65. These teeth mesh with a worm 66 on a shaft aligned with and engaging the armature shaft of the 100 motor 67. Accordingly this motor, by rotating the worm-wheel nut, may screw the shaft 52 in one direction or the other, as required, while when the motor is stationary the system is locked and the cradle held ac-
105 cordingly.

To prevent damage to the parts in case the cradle should be brought to a stop in either direction while the motor is still running there is provided a slip connection between the worm teeth and the nut. This is accomplished by making these worm teeth on a ring separate from the nut but surrounding it and held to it frictionally. To effect the frictional holding there is provided 110 a ring 70 overlapping the nut and the ring carrying the worm teeth and drawn toward these parts by springs 71 surrounding bolts 72 extending through them. Suitable ball bearings 73 and 74 may take the thrust of 115 the worm wheel nut in either direction. The casing 60 is preferably made separable, as indicated by the removable portion 75, to allow access to the interior. This interior is packed with grease, which is retained in 120 place by the stuffing box 76 surrounding the rod 52.

If desired an automatic magnetic brake may be provided on the armature shaft for stopping its rotation instantly when the cur-
130

rent is shut off. The exterior of this brake is indicated at 79 in Figs. 3 and 5 and a suitable construction thereof is described in the patent referred to.

5 Having thus described our invention, what we claim is:

1. The combination of a truck frame having a forward housing and a rear extension, a bracket mounted on said rear extension, 10 a load carrier pivoted to the top of the bracket, said bracket having a depending portion, a toggle joint having its links pivoted respectively to the depending portion of the bracket and to the load carrier at the 15 rear of its pivotal engagement with the bracket, a longitudinal rod connected with the knuckle of the toggle, and motor mechanism mounted in the housing for operating said rod.
- 20 2. The combination of a truck frame, a bracket at the rear end thereof, a load carrier pivoted to the top of the bracket, a toggle joint having its links pivoted respectively to a support at the rear end of the 25 frame and to the load carrier at the rear of its pivotal engagement with the bracket, a casing carried by the truck, a longitudinally movable rod extending into said casing and connected with the toggle joint, a motor and 30 gearing carried by said casing for moving said rod longitudinally.
3. The combination of a truck having supporting wheels, a front housing and a rear frame extending from the lower portion 35 of the housing, a bracket secured to the rear frame and extending toward the rear and both upwardly and downwardly, a load carrier pivoted to the upper end of the bracket, a toggle joint having its links connected respectively with the lower end of 40 the bracket and with the load carrier beyond

its pivotal connection to the bracket, motor mechanism supported within the housing, and a connection between the same and the knuckle of the toggle.

45

4. The combination of a truck having supporting wheels, a front housing and a rear frame extending from the lower portion of the housing, a bracket secured to the rear frame and extending upwardly and toward the rear, a load carrier pivoted to the upper end of the bracket, a toggle joint having its links connected respectively with a lower end portion of the frame and with the load carrier beyond its pivotal connection to the bracket, motor mechanism within the housing, connecting mechanism between the same and the knuckle of the toggle, and a bracket carried by the rear face of the housing for supporting the forward end of the load carrier.

50

5. The combination with a truck having supporting wheels and a rearwardly extending frame, comprising two longitudinal beams side by side and spaced apart, a bracket secured to the rear portion of each beam, said bracket extending diagonally upwardly and rearwardly, a load carrier, a shaft carried by said brackets for supporting the load carrier pivotally thereon, a housing at the front end of said frame, a bracket on the rear of the housing for supporting the forward end of the load carrier when horizontal, a toggle mechanism for swinging the load carrier, and motor mechanism within the housing for operating the toggle mechanism.

55

In testimony whereof we hereunto affix our signatures.

MORRIS S. TOWSON.
CLYDE E. COCHRAN.
